UNITED STATES PATENT OFFICE.

OTTO JAEGER, OF ELKINS PARK, PENNSYLVANIA, ASSIGNOR TO HARRY S. KELSEY, OF BOSTON, MASSACHUSETTS.

DISPENSING DEVICE.

1,268,249.

Specification of Letters Patent. Patented June 4, 1918.

Application filed March 23, 1917. Serial No. 156,838.

To all whom it may concern:

Be it known that I, Otto Jaeger, a citizen of the United States, and a resident of Elkins Park, county of Montgomery, and 5 State of Pennsylvania, have invented certain new and useful Improvements in Dispensing Devices, of which the following is a full, clear, and exact disclosure, reference being had to the accompanying drawings, 10 forming a part of this specification.

My invention relates to improvements in dispensing devices of the type comprising a casing inclosing a chamber and provided with two doors by means of which access 15 may be had to the interior of the chamber for the insertion or removal of the article or articles to be dispensed; and the object of my invention is to provide a device of this type of novel, simple and efficient construction, including means whereby the doors 20 may be operated and controlled.

With this object in view, my invention consists in the novel construction and combinations of parts hereinafter fully described and claimed.

In the accompanying drawings, illustrating my invention:

Fig. 1 is a rear elevation of a dispensing device embodying my invention.

30 Fig. 2 is a vertical section, on line 2—2 of Fig. 1, showing the doors in the closed position.

Fig. 3 is a view similar to Fig. 2, showing the front door in the open position and 35 showing certain other parts in a different position.

Fig. 4 is a vertical section of the device, showing the doors closed.

Fig. 5 is a view similar to Fig. 4, showing the front door in the open position and 40 showing certain other parts in a different position.

Fig. 6 is a horizontal section, on line 6—6 of Fig. 4.

45 Fig. 7 is a horizontal section, on line 7—7 of Fig. 4.

Referring to the drawings, 8 designates a 50 frame or casing having walls which inclose a chamber 9 adapted to receive the article or articles to be dispensed.

The casing 8 is provided with a rear door 10 which is hinged thereto, at 11, and which normally closes the back of the chamber 9.

The door 10 is held in its normal or closed position by a spring latch 12 which is secured to the bottom of the floor 13 of the chamber 9 and projects rearwardly beneath the floor 13 and door 10 and has a beveled nose 14 on its rearward end which engages the door 10. When the latch 12 is depressed 55 by hand from the bottom of the door 10 the door 10 may be raised on its hinge 11 to the dot-and-dash line position shown in Fig. 4 to afford access from the rear of the casing 8 to the interior of the chamber 9.

The casing 8 is provided with a front door 15 which is pivoted or hinged on two alined screw studs 16 which are screwed into the side walls 17 of the chamber 9, as clearly shown in Fig. 6. This door 15 is movable 60 on its hinge 16 from the position shown in Fig. 4 to the position shown in Fig. 5, and back again, to afford access to the interior of the chamber 9 from the front of the frame or casing 8.

One side of the door 15 is provided with an arm 18 which extends rearwardly from the hinge 16 and is pivoted, at 19, to the lower portion of a weight 20 which tends to lower the arm 18 and thereby raise the door 80 15 from the position shown in Fig. 4 to the position shown in Fig. 5. The upper portion of the weight 20 has a notch 21 formed therein which embraces a projection 22 on the upper end of a guide plate 23. The plate 23 is fitted against the forward face of a wall 24 of the frame or casing 8; and fitted against the rearward face of the wall 24 is a block 25 which is connected to the plate 23 by screws 26 which extend through a guide 90 slot 27 in the wall 24, whereby, when the weight 20 moves from the position shown in Fig. 4 to the position shown in Fig. 5, the block 25 will be moved down to the position shown in Fig. 5. When the block 25 is in 95 the position shown in Fig. 5, a roller 28 carried thereby is in the path of the rear door 10, so that, when the rear door 10 is opened from the position shown in Fig. 5 to the position shown by dot-and-dash lines in Fig. 4, the door 10 will engage the roller 28 and raise the block 25 and weight 20 to the position shown in Fig. 4, thereby closing the front door 15.

In addition to the weight 20, I provide a 105 spring 29, having one end attached to the

weight 20 and the other end attached to the frame or casing 8, and which tends to pull the weight 20 down from the position shown in Fig. 4 and thereby assists in opening the front door 15. Just before the weight 20 reaches the position shown in Fig. 5, during its downward movement, the spring 29 is compressed and it thus acts as a cushion for the weight as it comes to rest in the position shown in Fig. 5.

To hold the front door 15 firmly in its open position shown in Fig. 5, I provide a flat spring 29^a secured at one end to a projection 30 on the casing 8 and provided at its free end with oppositely inclined portions forming a hump 31 which is engaged by a pin 32 projecting from the arm 18. When the door 15 is moved by force from its open to its closed position and back again, the spring 29^a yields and the pin 32 passes from side to side of the hump 31.

When the front door 15 is moved to the closed position, shown in Fig. 4, it is retained in this position against the action of the weight 20 and spring 29 by devices which I shall now describe. One side of the door 15 is provided with an arm 33 which extends rearwardly from the hinge 16 and bears at its free end upon a dog 34 which, in effect, is a part of a member 35 which is pivoted, at 36, to the casing 8. The weight 20 presses the arm 33 down upon the dog 34 and thereby tends to move the member 35 on its pivot 36 away from the arm 33 to free the arm 33 from the dog 34. The member 35 is prevented from moving away from the arm 33 by a latch 37 which is pivoted to the member 35 and has a hooked end which engages a shoulder 38 formed on a bracket 39 on the casing 8. The latch 37 is adapted to be raised from engagement with the shoulder 38 by an arm 40 which is pivoted, at 41, to the bracket 39, and said latch 37 is movable from engagement with the shoulder 38 to the position shown in Fig. 3 and back again into engagement with the shoulder. The arm 40 or latch 37 may be raised by hand or by any suitable devices to free the latch from the shoulder 38. When the latch 37 is thus raised, and the member 35 thereby freed, the weight 20 forces the arm 33 down and causes it to force the dog 34 and member 35 away from the arm 33 to the position shown in Fig. 3, thereby freeing the arm 33 and permitting the weight 20 and spring 29 to open the front door 15 and move the arm 33 down to the position shown in Fig. 3. Immediately after the arm 33 escapes the dog 34, the member 35 automatically returns by gravity to the normal position shown in Fig. 2, and the latch 37 returns by gravity into position to engage the shoulder 38 when the member 35 reaches its said normal position.

The lower end of the dog 34 is pivoted, at

42, to the member 35. A part 43 of the dog 34 engages the member 35, and the part 43 is maintained normally against the member 35 to hold the dog 34 in its normal position on the member 35 by a suitable spring 44 secured to the member 35 and engaging the dog 34. The connections between the dog 34 and the member 35 and the location of the pivot 42 with relation to the engagement of the arm 33 with the dog 34 are such that the pressure of the weight 20 holds the part 43 of the dog 34 against the member 35 and tends to move the member 35 away from the arm 33 and hold the latch 37 against the shoulder 38, as previously explained.

After the arm 33 moves to the position shown in Fig. 3, and the member 35 and latch 37 return by gravity to the position shown in Fig. 2, the door 15 is closed by opening the door 10, as previously explained, thereby moving the arm 33 back to the position shown in Fig. 2. As the arm 33 is thus moved back to this position it engages the dog 34 and forces it back against the spring 44, until the end of the arm 33 escapes the top of the dog 34, whereupon the dog 34 springs back to its normal position shown in Fig. 2, and then, when the arm 33 is released, it again rests upon the top of the dog 34 to retain the door 15 in its closed position.

The arm 33 is provided with a projection 45 which is adapted to engage the arm 40 and return it to the position shown in Fig. 3, when the arm 33 is moved to the position shown in Fig. 2, the arm 40 being adapted to be retained in the positions to which it is moved by its frictional engagement with parts of the machine.

When the front door 15 is moved from its closed position shown in Fig. 4, a part 46 is moved from the position shown in Fig. 4 to the position shown in Fig. 5 and into the space occupied by the free end of the door 15 when closed, thereby preventing the complete closing of the door 15 until the return of the part 46 to the position shown in Fig. 4, for a purpose hereinafter explained, and I shall now describe the means for moving the part 46. The part 46 rests upon the compartment floor 13 and is provided with an arm 47 which extends down through a guide slot 48 in the floor 13. Screwed into the arm 47 is one end of a rod 49 which extends rearwardly from the arm 47 and into a tube 50. The tube 50 is slidable in bearings 51 which are secured to the bottom of the floor 13; and the outer end of the tube 50 is closed and rests normally against a projection 52 which extends downwardly from the bottom of the door 10. Encircling the rod 49 within the tube 50 is a spring 53 one end of which engages the closed end of the tube 50 and the other end of which engages a pin 54 extending trans-

versely through the rod 49. The spring 53 tends to move the part 46 from the position shown in Fig. 4 to the position shown in Fig. 5, when the doors 10 and 15 are closed so that when the front door 15 is opened, the spring 53 will project the part 46 to the position shown in Fig. 5, to prevent the complete closing of the door 15. The arm 47 is connected by a spring 55 to a pin 56 which extends downwardly from the floor 13; and the spring 55 tends to move the part 46, rod 49, spring 53 and tube 50 back to the dot-and-dash line position, shown in Fig. 5. The action of the springs 53 and 55 is such that when the front door 15 is opened, while the rear door remains closed, the spring 53 will project the part 46 to the position shown in Fig. 5; and that, thereafter, when the rear door 10 is opened and the projection 52 thereby moved from the end of the tube 50, the spring 53 having spent itself, spring 55 will move the part 46, rod 49, spring 53 and tube 50 bodily back from the position shown by full lines 25 to the position shown by dot-and-dash lines in Fig. 5, thereby permitting the front door 15 to be completely closed by the action of the upward movement of the rear door 10 against the roller 28, as previously explained.

The operation of the device, briefly described, is as follows:

The frame or casing 8 is usually placed to form part of a partition wall which separates the customer for the article or articles to be dispensed from the machine attendant, the customer receiving the article or articles in a position in front of the casing adjacent to the front door 15, and the attendant supplying the chamber 9 with the article or articles to be dispensed from a position in rear of the casing 8 adjacent to the rear door 10.

Assuming that the chamber 9 is supplied with the article or articles to be dispensed and that the parts are in the position shown in Figs. 1, 2 and 4, the arm 40 is raised. This may be done by the hand of the attendant after he receives the purchase price 50 of the article or articles to be dispensed, or it may be done by suitable coin controlled devices operated by the customer in front of the casing 8 by the insertion therein of a coin or coins representing the purchase price 55 of the article or articles to be dispensed.

The raising of the arm 40 lifts the latch 37 from engagement with the shoulder, thereby freeing the member 35 and permitting the arm 33, under the influence of the weight 20 and spring 29, to move the dog 34 and member 35 to the position shown in Fig. 3, thus freeing the arm 33 and permitting the weight 20 and spring 29, to move 60 the arm 33 to the position shown in Fig. 3,

and thus open the front door 15 or move it to the position shown in Figs. 3 and 5. When the front door 15 is thus opened, the customer may remove the article or articles to be dispensed from the chamber 9. 70

Immediately after the front door 15 leaves its closed position, the member 35 and latch 37 return by gravity from the position shown in Fig. 3 to the full line position shown in Fig. 2, the free end of the latch 37 returning by gravity to a position to reengage the shoulder 38. The attendant now depresses the latch 12 and raises the rear door 10 to the position, shown by dot-and-dash lines in Fig. 4, and recharges the chamber 9 with another article or articles to be dispensed. The attendant then closes the rear door 10, and, as he moves it to its closed position, it engages the beveled nose 14 of the latch 12 and depresses it, and the latch 12 thereafter springs up and retains the rear door 10 in its closed position. 80

As the attendant raises the rear door 10 to the dot-and-dash line position shown in Fig. 4, the door 10 engages the roller 28 and raises the block 25 and weight 20 to the position shown in Fig. 2, and thereby closes the front door 15. As the front door 15 moves to its closed position, its arm 33 is raised to a position above the dog 34, and, 95 during this operation, the dog 34 is moved back against the action of its spring 44 until the arm 33 escapes the upper end of the dog, whereupon the dog springs out under the free end of the arm 33 in the 100 position shown in Fig. 2; and, when the upward pressure of the door 10 against the roller 28 is removed, the arm 33 engages the dog 34 which locks the front door 15 in its closed position against the weight 20 and 105 spring 29 for a succeeding opening operation.

When the front door was opened, as previously explained, the spring 53 projected the part 46 from the position shown in Fig. 4 to the position in Fig. 5 and into the space occupied by the free end of the door 15 when it was in its closed position, and, therefore, the part 46 in this projected position prevents a customer or any one in 115 front of the casing 8 from closing the door 15, should he attempt to do so, sufficiently to move the free end of the arm 33 above the top of the dog 34. When, however, the front door 15 is closed by the attendant 120 opening the rear door 10, as previously explained, the projection 52 on the rear door 10 is moved away from the closed end of the tube 50, permitting the spring 55 to move the part 46, rod 49, spring 53 and tube 50 back to the dot-and-dash line position shown in Fig. 5, and thereby permitting the front door 15 to be completely closed and the arm 33 to be moved to a position above the dog 34 by the opening of the rear door 130

10. It will thus be seen that the front door 15 will remain open to indicate to the customer that the chamber 9 is empty, until the chamber 9 is recharged by the attendant who, upon recharging the chamber, 15 raises the rear door 10 to gain access thereto and thereby closes the front door 15. After the attendant recharges the chamber 9, he closes the rear door 10; and, as the door 10 moves to its closed position, the projection 15 52 engages the outer end of the tube 50 and moves it and the spring 53, rod 4 and part 46 bodily toward the door 15 against the action of the spring 55 until the part 46 20 engages the front door 15, as shown in Fig. 4, and, after the part 46 engages the door 15, the continued movement of the door 10 to its closed position, places the spring 53 under compression so that it will force the 25 part 46 out to the position shown in Fig. 4 when the door 15 is opened to prevent the closing of the door 15 until the rear door 10 is opened, as previously explained.

When the part 46, rod 49, spring 53 and tube 50 are in the dot-and-dash line position shown in Fig. 5, the spring 53 is in a spent condition; that is to say, it has no force tending to move the part 46 relatively to the tube 50. When, however, the parts are in 30 the position shown in Fig. 4, the spring 53 is compressed and its force, tending to move the part 46 to the position shown in Fig. 5, is greater than the pull of the spring 55 which moves the part 46, rod 49 and tube 35 5 bodily to the dot-and-dash line position shown in Fig. 5, when the rear door 10 is opened.

After the attendant has recharged the chamber 9 and closed the rear door 10, the 40 parts are left in the position shown in Figs. 1, 2 and 4 for a succeeding operation.

I claim:

1. In a dispensing device, the combination of a casing having a front door and a rear door each being movable to open and closed positions and affording access to the interior of the casing, means operative to lock the front door in the closed position when it is moved thereto and the rear door is away 45 from its closed position, and means controlled by the rear door to prevent the operation of the first named means when the rear door is in the closed position.

2. In a dispensing device, the combination of a casing having a front door and a rear door each being movable to open and closed positions and affording access to the interior of the casing, means operative to lock the front door in the closed position 55 when it is moved thereto and the rear door is away from its closed position, a part movable into and from an operative position, said part preventing the operation of said means when in the operative position and 60 permitting the operation of said means when

in the inoperative position, and means controlled by the rear door to automatically move said part to the inoperative position when the rear door is moved from its closed position.

3. In a dispensing device, the combination of a casing having a front door and a rear door each being movable to open and closed positions and affording access to the interior of the casing, a block slidable on and 70 guided by a part of the casing, said rear door and said block having co-operating parts causing said block to move in one direction when said rear door is moved to its open position, means operative to move said block in the reverse direction, and means operated by said block when it is moved by said rear door to move the front door to its closed position.

4. In a dispensing device, the combination of a casing having a front door and a rear door each being movable to open and closed positions and affording access to the interior of the casing, a part adapted to engage the front door and movable into and 80 from an operative position preventing the front door from being moved to its closed position, and means to automatically move said part from its operative position when the rear door is moved to its open position.

5. In a dispensing device, the combination of a casing having a front door and a rear door each being movable to open and closed positions and affording access to the interior of the casing, a part adapted to engage the front door and movable into and from an operative position preventing the front door 90 from being moved to its closed position, means to automatically move said part from its operative position when the rear door is moved to its open position, and means to automatically move said part to its operative position when the front door is moved from its closed position.

6. In a dispensing device, the combination of a casing having a front door and a rear door each being movable to open and closed positions and affording access to the interior of the casing, a part adapted to engage the front door and movable into and 110 from an operative position preventing the front door from being moved to its closed position, means to automatically move said part from its operative position when the rear door is moved to its open position, and means to automatically move the front door to its closed position when the rear door is moved to its open position.

7. In a dispensing device, the combination of a casing having a front door and a rear 125 door each being movable to open and closed positions and affording access to the interior of the casing, a part adapted to engage the front door and movable into and from an operative position preventing the front door 130

from being moved to its closed position, means to automatically move said part from its operative position when the rear door is moved to its open position, means to automatically move said part to its operative position when the front door is moved from its closed position, and means to automatically move the front door to its closed position when the rear door is moved to its open position.

8. In a dispensing device, the combination of a casing having a front door and a rear door each being movable to open and closed positions and affording access to the interior of the casing, means to automatically move the front door to its open position when released, a part adapted to engage the front door and movable into and from an operative position preventing the front door from being moved to its closed position, and means to automatically move said part to its operative position when the front door is moved from its closed position, and means to automatically move said part from its operative position when the rear door is moved to its open position.

9. In a dispensing device, the combination of a casing having a front door and a rear door each being movable to open and closed positions and affording access to the interior of the casing, means to lock the front door in its closed position and operative to release the same, means to automatically move the front door to its open position when released, a part adapted to engage the front door and movable into and from an operative position preventing the front door from being moved to its closed position, and means to automatically move said part to its operative position when the front door is moved from its closed position, and means to automatically move said part from its operative position when the rear door is moved to its open position.

45 10. In a dispensing device, the combination of a casing having a front door and a rear door each being movable to open and closed positions and affording access to the interior of the casing, means to automatically move the front door to its open position when released, a part adapted to engage the front door and movable into and from an operative position preventing the front door from being moved to its closed position, and means to automatically move said part to its operative position when the front door is moved from its closed position, means to automatically move said part from its operative position when the rear door is moved to its open position, and means to automatically move the front door to its closed position when the rear door is opened.

11. In a dispensing device, the combination of a casing having a front door and a rear door each being movable to open and

closed positions and affording access to the interior of the casing, means to lock the front door in its closed position and operative to release the same, means to automatically move the front door to its open position when released, a part adapted to engage the front door and movable into and from an operative position preventing the front door from being moved to its closed position, and means to automatically move said part to its operative position when the front door is moved from its closed position, means to automatically move said part from its operative position when the rear door is moved to its open position, and means to automatically move the front door to its closed position when the rear door is moved to its open position.

12. In a dispensing device, the combination of a casing having a front door and a rear door each being movable to open and closed positions and affording access to the interior of the casing, means to automatically move the front door to its open position when released, means to automatically move the front door to its closed position when the rear door is moved to its open position, and means to automatically lock the front door in its closed position when it is moved thereto, the last named means being operative to release the front door, a part adapted to engage the front door and movable into and from an operative position preventing the front door from being moved to its closed position, and means to automatically move said part to its operative position when the front door is moved from its closed position, and means to automatically move said part from its operative position when the rear door is moved to its open position.

13. In a dispensing device, the combination of a casing having a front door and a rear door each being movable to open and closed positions and affording access to the interior of the casing, a part adapted to engage the front door and movable into and from an operative position preventing the front door from being moved to its closed position, and a spring device adapted when in operative position to move said part into operative position when the front door is moved from its closed position, said device being adapted to be moved to its operative position by the rear door when it is moved to its closed position.

14. In a dispensing device, the combination of a casing having a front door and a rear door each being movable to open and closed positions and affording access to the interior of the casing, a part adapted to engage the front door and movable into and from an operative position preventing the front door from being moved to its closed position, a spring device adapted when in

- operative position to move said part into operative position when the front door is moved from its closed position, said device being adapted to be moved to its operative 5 position by the rear door when it is moved to its closed position, a latch adapted to hold the rear door in its closed position and operative to release the same, and means to automatically move said part and said device 10 from their operative positions when the rear door is released.
15. In a dispensing device, the combination of a casing having a front door and a rear door each being movable to open and closed positions and affording access to the interior of the casing, a part adapted to engage the front door and movable into and from an operative position preventing the front door from being moved to its closed 20 position, a latch adapted to hold the rear door in its closed position and operative to release the same, a tube movable into and from an operative position and adapted to be moved to its operative position and to be 25 held therein by the rear door when it is moved to its closed position and held therein by said latch, and a spring within said tube and adapted to move said part to its operative position when the tube is in its operative 30 position and the front door is moved from its closed position.
16. In a dispensing device, the combination of a casing having a front door and a rear door each being movable to open and closed positions and affording access to the interior of the casing, a part adapted to engage the front door and movable into and from an operative position preventing the front door from being moved to its closed 35 position, a latch adapted to hold the rear door in its closed position and operative to release the same, a tube movable into and from an operative position and adapted to be moved to its operative position and to be 40 held therein by the rear door when it is moved to its closed position and held therein by said latch, a spring within said tube and adapted to move said part to its operative position when the tube is in its operative 45 position and the front door is moved from its closed position, and means to automatically move said part and said tube and the spring therein from their operative positions when the rear door is released.
50. 17. In a dispensing device, the combination of a casing having a front door and a rear door each being movable to open and closed positions and affording access to the interior of the casing, a movable block guided by the casing, said block having a part in the path of movement of the rear door when it is closed and the front door is open, and said part being adapted to be engaged by the rear door when it moved to its open position to move said block therewith, and means 55 operated by said block when moved by the rear door to move the front door to its closed position.
18. In a dispensing device, the combination of a casing having a front door and a rear door each being movable to open and closed positions and affording access to the interior of the casing, an arm projecting from said front door, a movable block guided by the casing, and a weight pivoted to said 70 arm and engaging said block and tending to move the front door from its closed to its open position and tending to move said block from a normal position, said block having a part which is moved into the path of the back door when the back door is in its closed position and the front door is moved to its open position by said weight, whereby when the back door is moved to its open position, it will engage said part and act 75 upon said block and weight to move the front door to its closed position.
19. In a dispensing device, the combination of a support, a door controlling part movable from a normal position to control 80 the opening of a door, means tending to move said part from its normal position, a member provided with means engaging said part and holding it in its normal position, the first named means tending to move said 85 member from a normal position to release said part, and a latch device holding said member in its normal position and operative to release the same.
20. In a dispensing device, the combination of a support, a door controlling part movable from a normal position to control 90 the opening of a door, means tending to move said part from its normal position, a member provided with a spring pressed dog engaging said part and holding it in its normal position, said means tending to move said member and its dog from a normal position to release said part, whereby when said member is released, said means will automatically 95 move it and said part from their normal positions, said dog permitting the return of said part to its normal position without moving said member after it is returned to its normal position.
21. In a dispensing device, the combination of a support, a door controlling part movable from a normal position to control 100 the opening of a door, means tending to move said part from its normal position, a member provided with means engaging said part and holding it in its normal position, said member being movable from a normal position to which it automatically returns after being moved therefrom, the first named 105 means tending to move said member from its normal position to release said part, and a latch device adapted to automatically hold 110
- 115
- 120
- 125

said member in its normal position when moved thereto and being operative to release said member.

22. In a dispensing device, the combination of a support, a door controlling part movable from a normal position to control the opening of a door, means tending to move said part from its normal position, a member provided with a spring pressed dog 5 engaging said part and holding it in its normal position, said member being movable from a normal position to which it automatically returns after being moved therefrom, said means tending to move said member and its 10 dog from a normal position to release said 15 part, and a latch device adapted to automatically hold said member in its normal position when moved thereto and being operative to release said member, whereby when said member is released, said means will automatically move it and said part from their normal positions, said dog permitting the return of said part to its normal position without moving said member after it returns to its normal position and is held 20 therein by said latch device. 25

In witness whereof, I have hereunto set my hand this 19th day of March, 1917.

OTTO JAEGER.
